MACHINE FOR SHAPING UPPERS OVER
LASTSJoseph C. Lisbon, Sr., Haverhill, Mass., assignor
to United Shoe Machinery Corporation, Paterson, N. J., a corporation of New Jersey

Application December 27, 1934, Serial No. 759,408

28 Claims. (Cl. 12—2)

This invention relates to machines for shaping uppers over lasts, and is herein illustrated as applied to a lasting machine having means for pulling an upper over a last successively in different locations along the edge of the shoe bottom, and means for laying the marginal portion of the tensioned upper inwardly over the bottom of the last in time relation to each upper-pulling operation, the machine herein shown having also means for fastening the upper by driving staples and curving their legs progressively as they are driven to anchor them in the shoe, as disclosed in United States Letters Patent No. 1,815,295, granted on July 21, 1931 upon an application of George Goddu. It is to be understood, however, that the invention in its more general aspects is not limited to machines of the particular type illustrated.

An object of the invention is to provide an improved machine adapted for use in lasting shoes of that type in which a portion at least of the upper is secured by an adhesive in lasted relation to a sole or insole (hereinafter frequently referred to as the sole). Machines of the type disclosed in the above-mentioned Letters Patent include in their organization overlaying means movable inwardly over the bottom of a last in a direction inclined toward its bottom face to lay the marginal portion of the upper over a sole on the last, and mechanism for driving a staple after each overlaying operation and for curving the legs of the staple to anchor them in the sole. Such machines have also means for feeding staple wire and for forming staples, together with means which may be used at will to stop the feed of the wire, so that no staple will be driven in the cycle of operations. It is contemplated that for purposes of this invention the feed of the wire will thus be interrupted to permit the machine to be used in lasting with an adhesive instead of with staples; and a particular object of the invention is to improve the results obtained under such conditions. To this and other ends, the invention, in one important aspect, provides means which is arranged in each cycle of the machine to force by impact against the shoe bottom a portion of the margin of the upper laid inwardly over the sole in an earlier movement of the overlaying means. This means, as herein shown, comprises a resilient member which is arranged

to engage the overlaid marginal portion of upper over substantially its entire width in a different location lengthwise of the edge of the shoe bottom from that of the overlaying means. The resilient member is normally out of contact with the shoe bottom, and connected to the staple-driving means is a member for imparting to the resilient member a hammer blow to force it against the upper. The resilient member is thus operated substantially at the end of each overlaying operation and while the overlaying means is in pressure-applying position to pound against the shoe bottom a portion of the margin of the upper previously laid inwardly over the sole by the overlaying means. In the use of the machine for lasting shoes with cement, as the shoe is presented to the machine by the operator in different positions in the progressive lasting of its opposite sides, the resilient member acts to beat against the shoe bottom for substantially its entire width the tensioned and overlaid margin of the upper. Not only is the upper thus pressed flat against the bottom face of the sole to provide a smooth bottom but, moreover, sufficient pressure is also applied to insure firm and permanent adherence of the upper to the sole.

The above and other features of the invention, including various novel details of construction and combinations of parts, will now be more particularly described by reference to the accompanying drawings and pointed out in the claims.

In the drawings,

Fig. 1 is a view in side elevation of a portion of the head of a machine in which the invention is embodied, showing the parts in the positions that they occupy when the machine is initially at rest;

Fig. 2 is a view in front elevation of a portion of the head of the machine shown in Fig. 1, showing the wire-feeding means and the mechanism for stopping the feeding of the wire;

Fig. 3 is a view in side elevation of a portion of the mechanism shown in Fig. 1, with the parts in the positions that they occupy at the end of the overlaying operation;

Fig. 4 is a view similar to Fig. 3, but showing the positions of the parts at the completion of the upper-pounding operation;

Fig. 5 is a perspective view illustrating the relative positions of the gripper and the upper-pounding means; and

Fig. 6 is a detail view of the upper-pounding member.

Since the invention, as above stated, is illustrated as embodied in a machine of the type disclosed in the previously mentioned Letters Patent, only such features of the general organization as it is necessary to refer to for an understanding of the invention will be described herein in detail.

- 10 It will be understood that the shoe and last are supported bottom upward in the hands of the operator and presented successively in different locations in the progressive lasting of its opposite sides. To assist in determining the proper relation of the shoe to the lasting instrumentalities the machine is provided with a side gage 10 arranged to engage the side of the shoe at or near the edge of the insole and with a sole rest 12 for engaging the bottom face of the insole at a considerable distance from its edge. The side gage 10 is mounted on a bracket 14 which is adjustable along a guideway 16 formed in the head of the machine and is held in adjusted position by a cap screw 18. The sole rest 12 is supported by a bracket 20 which is adjustable horizontally in a guideway formed in the head of the machine and is held in adjusted position by a cap screw 22. The upper is pulled over the last and inwardly over the insole when the shoe is in each lasting position by a gripper comprising a pair of jaws 24. For laying the marginal portion of the upper inwardly over the insole and fastening it with staples there is provided a slide or carrier 26 which is moved by a cam 28 along a straight guideway 30 in a forwardly and downwardly inclined direction at an angle to the bottom face of the last and shoe. This slide carries a staple guide or nozzle 32, a staple driver 34 and a deflector 36 which engages the legs of the staple and curves them prior to and during their entrance into the shoe. The operative movement of the driver is in a rearward direction and the deflector curves the legs of the staple forwardly away from the edge of the insole. It will be understood that prior to the driving of the staple the marginal portion of the upper is pulled inwardly over the insole by the gripper and is laid over and upon the outer face of the insole by the nozzle 32 and deflector 36 in the forward movement of the slide 26. Substantially at the end of the forward movement of the slide along its guideway 30 the staple nozzle and deflector receive a short downward movement more directly toward the shoe bottom which is effected by swinging the slide 26 about the axis of a rockshaft 38 (Fig. 1). For this purpose a member 40 on which the guideway 30 is formed is mounted on a holder 42 which is fast on the rockshaft 38 and fast also on the rockshaft is a lever 44 operated by a cam 46 to swing the slide 26 as described. In this manner insurance is afforded that the upper will be pressed firmly upon the insole and that the staple nozzle and deflector will be close to the shoe bottom when the staple is driven.

Means substantially as disclosed in the above mentioned Letters Patent is provided for operating the staple driver 34. The driver is fastened to a driver slide 48 which is movable in a downwardly and rearwardly inclined direction in a guideway formed in a bracket 50 secured to a forward extension of the slide 26. The driver slide 48 is operated by a lever 52 which is pivoted on a stud 54 on a forward extension of the slide 26 and carries a lug 56 extending into a recess

in the driver slide. The lever 52 is operated by a bell-crank lever 58 which is pivoted on a rod 60 on the slide 26 and is operated by a torsion spring 62 (Fig. 2). The forwardly extending arm of the bell-crank lever 58 carries a roll 64 which operates in a cam slot 66 in the lever 52, the cam slot being so formed that the staple-driving movement is imparted to the lever 52 by upward movement of this arm. For swinging the bell-crank lever 58 against the resistance of its operating spring to retract the driver 34 and to tension the spring there is pivoted at 68 on the head of the machine a lever 70 on which is pivotally mounted at 72 a latch 74 arranged to engage the lower end of a plate 76 fast on a downwardly extending arm on the bell-crank lever 58. A spring 78 connected to the latch 74 and to a pin 80 on the lever 70 holds the latch in operative relation to the plate 76 when the slide 26 and the parts carried thereby are in their initial positions. When the slide is moved forwardly toward the shoe the latch 74 acts to swing the bell-crank lever 58 against the resistance of its spring in response to such forward movement, thereby operating the lever 52 to retract the staple driver 34 as the latter is being carried bodily forward by the slide 26. For operating the latch 74 to release the lever 58 and thus to cause the operation of the driver the slide 26 carries a screw 82 the head of which is arranged to engage a shoulder on the latch. The forward movement of the slide 26, however, does not carry the screw far enough to release the lever 58, such release being effected in response to a swinging movement of the latch carrying lever 70 effected by a cam 84 after the slide 26 has completed its forward movement. It will be understood that by reason of such movement of the lever 70 the screw 82 causes the latch 74 to swing far enough to disconnect it from the plate 76. In the return of the parts to starting positions the latch 74 is held by a shoulder 86 on the lever 70 in position to connect again with the plate 76 when the slide 26 arrives at the end of its retractive movement.

The machine is also provided with means fully disclosed in the previously mentioned Letters Patent for forming a staple in response to the forward movement of the slide 26 and for transferring the staple from forming position into alignment with the driver 34, together with means for feeding wire intermittently to the staple-forming means. The wire from which the staples are formed is mounted on a reel (not shown) and is operated upon by feed wheels 88, 90 (Fig. 2) from which it is conducted through a flexible tube 92 to the staple-forming instrumentalities. The feed wheel 88 is operated by a pawl and ratchet mechanism through a link 94 and a bell-crank lever 96 provided with a roll 98 engaged by a cam 100. In order to stop the feed of the wire, so that no staple will be formed in the operation of the machine there is provided a lever 102 having thereon a projection 104 arranged to engage a face 106 on the lever 96 and thus to hold this lever in such a position as to prevent it from being operated by the cam 100. The illustrated machine as thus far described is substantially as disclosed in the above-mentioned Letters Patent.

For purposes of this invention there is provided a member or presser 108 which is arranged in each cycle of operations of the machine to force by impact against the bottom face of the insole a portion of the margin of the upper previously laid inwardly over the insole in an earlier movement of the overlaying means. This press-

er, which is preferably resilient, is clamped to the head of the machine by the bracket 14 and extends inwardly over the bottom of the shoe at one side of the staple-guiding nozzle and deflector and the gripper (Figs. 2 and 5) in position to act on a portion of the upper previously laid inwardly over the insole by the staple-guiding nozzle and deflector. The presser 108 is supported by the bracket 14 slightly above the plane of the shoe bottom and has formed in its rearward portion a lengthwise slot 109 (Fig. 6) through which the cap screw 18 extends, so that by loosening the cap screw the presser may be adjusted widthwise of the shoe to engage the overlaid margin of the upper for substantially its entire width. For operating the presser 108 to pound the upper at the proper time in the cycle of the machine there is secured to the driver-operating slide 48 a member 110. The member 110 is provided with a rearwardly extending arcuate portion 112 which is arranged as the member 110 is moved toward the shoe by the slide 48 to engage an upstanding lip 114 formed on the forward end of the presser. It will be seen that since the slide 48 moves toward the shoe in a downwardly and rearwardly inclined direction, the presser 108 is forced downwardly against the upper as the arcuate portion 112 of the member 110 engages the lip 114. The presser thus acts to force by impact against the shoe bottom a portion of the margin of the upper laid inwardly over the insole in an earlier movement of the staple-guiding nozzle and deflector.

It will be understood that in the use of the machine for lasting shoes without staples, as by the use of cement, the operator will swing the lever 102 to the position shown in Fig. 2 to interrupt the feed of the wire to the staple-forming instrumentalities of the machine, thereby rendering the fastening-inserting mechanism ineffective to insert fastenings. In operation, as the shoe is presented by the operator successively in different locations in the progressive lasting of its opposite sides, portions of the upper previously laid over and pressed upon the insole by the overlaying means will be forced into firm and permanent adherence to the insole over a comparatively wide area as the presser 108 is operated by the fastening-inserting mechanism to beat the upper against the shoe bottom. It will be further understood that the presser is thus operated in each cycle of the machine after the overlaying means has completed its inward movement to lay a portion of the margin of the upper over the insole and its movement in a different direction to increase its pressure on the upper and while the portion thus overlaid is held pressed against the insole. It will be evident that a machine constructed as above-described may be used to last a shoe in which the upper is fastened to the shank portion of the insole by staples and along the sides of the forepart by cement. In the use of the machine for driving staples the presser 108 acts on the lasting margin of the upper over a comparatively wide area to force it flat upon the bottom face of the insole.

While the invention is herein illustrated as applied to a machine having means for driving upper-fastening staples, it should be understood that it is not limited to an organization which drives fastenings of that particular character.

Having described my invention, what I claim as new and desire to secure by Letters Patent of the United States is:

1. In a machine for shaping uppers over lasts, overlaying means movable inwardly over the bot-

tom of a last in a direction inclined toward its bottom face to lay the marginal portion of an upper over a sole on the last, means for beating the upper against the sole, and means movable with said overlaying means for operating the beating means. 5

2. In a machine for shaping uppers over lasts, overlaying means movable inwardly over the bottom of a last to lay the marginal portion of an upper over a sole on the last, means for beating the upper against the sole, and means movable 10 with said overlaying means for operating the beating means, said last-named means being operatively movable in time relation to the movement of the overlaying means.

3. In a machine for shaping uppers over lasts, 15 overlaying means movable inwardly over the bottom of a last to lay the marginal portion of an upper over a sole on the last, means for beating the upper against the sole, and means movable with said overlaying means for operating the 20 beating means, said last-named means being operatively movable in an outwardly inclined direction toward the edge of the shoe bottom in time relation to the movement of the overlaying means. 25

4. In a machine for shaping uppers over lasts, the combination with overlaying means movable inwardly over the bottom of a shoe for laying the marginal portion of an upper over a sole in position to adhere thereto through the action of cement, of a presser arranged to extend inwardly over the bottom of the shoe, and a member movable with said overlaying means for operating said presser by impact to cause it to force the margin of the upper more firmly against the sole. 30

5. In a machine for shaping uppers over lasts, an overlaying member movable inwardly over the bottom of a shoe for laying the marginal portion of an upper over a sole in position to adhere thereto through the action of cement, a carrier for 40 imparting to said overlaying member its inward movement, a presser arranged to extend inwardly over the bottom of the shoe at one side of the overlaying member, and means mounted on the carrier for delivering a hammer blow to said 45 presser substantially at the end of the inward movement of the overlaying member to cause the presser to force the margin of the upper more firmly into adhering relation to the sole.

6. In a machine for shaping uppers over lasts, 50 an overlaying member movable inwardly over the bottom of a shoe for laying the marginal portion of an upper over a sole in position to adhere thereto through the action of cement, a carrier for imparting to said overlaying member its inward movement, a presser arranged to overlie a portion of the margin of the upper previously laid inwardly over the sole by said overlaying member, and a spring-operated member on the carrier for striking the presser to cause it to force 60 the overlaid margin of the upper by impact against the sole.

7. In a machine for shaping uppers over lasts, 65 an overlaying member movable inwardly over the bottom of a shoe for laying the marginal portion of an upper over a sole in position to adhere thereto through the action of cement, a carrier for imparting to said overlaying member its inward movement, a presser arranged to extend inwardly over the bottom of the shoe in a location 70 in which the margin of the upper has been laid inwardly over the sole in an earlier movement of the overlaying member, a member mounted on said carrier for delivering a blow to said presser to cause it to force the overlaid margin of the upper 75

- by impact against the sole, a spring-operated lever for imparting to said member its operative movement, and means for swinging said lever in a direction to tension its operating spring in response to the inward movement of the overlaying member and for releasing said lever to the action of said spring substantially at the end of the inward movement of the overlaying member.
8. In a machine for shaping uppers over lasts, 10 an overlaying member, a carrier for moving said overlaying member inwardly over the bottom of a shoe to lay the marginal portion of an upper over a sole, a presser arranged to force against the bottom of the shoe a portion of the margin 15 of the upper previously acted upon by said overlaying member, a spring-operated hammer mounted on said carrier for delivering a blow to said presser, means for retracting said hammer and for tensioning its operating spring in response 20 to the inward movement of the carrier, and means arranged to act independently of the movement of the carrier for releasing said hammer to the action of its operating spring substantially at the end of the inward movement of the overlaying member.
9. In a machine for shaping uppers over lasts, 25 overlaying means movable inwardly over the bottom of a last to lay the marginal portion of an upper over a sole on the last, means for effecting a relative movement of said overlaying means and the last to increase the pressure of the overlaying means on the upper and means constructed to act while the upper is held under pressure by said overlaying means to force by impact against the shoe bottom a portion of the margin of the upper laid inwardly over the sole in an earlier movement of the overlaying means.
10. In a machine for shaping uppers over lasts, 30 overlaying means movable inwardly over the bottom of a last to lay the marginal portion of an upper over a sole on the last, means for effecting a relative movement of said overlaying means and the last after the overlaying means has substantially completed its inward movement to increase 35 the pressure of the overlaying means on the upper, and means constructed to act while the upper is held under pressure by said overlaying means to pound against the shoe bottom in a different location lengthwise of the shoe a portion 40 of the margin of the upper previously laid inwardly over the sole.
11. In a machine for shaping uppers over lasts, 45 overlaying means movable inwardly over the bottom of a last to lay the marginal portion of an upper over a sole on the last, means for effecting a relative movement of said overlaying means and the last to increase the pressure of the overlaying means on the upper, and a tool displaced lengthwise of the edge of the shoe bottom from 50 said overlaying means for pounding against the shoe bottom while the upper is held under pressure by said overlaying means a portion of the margin of the upper previously laid inwardly over the sole.
12. In a machine for shaping uppers over lasts, 55 overlaying means movable inwardly over the bottom of a last to lay the marginal portion of an upper over a sole on the last in position to adhere thereto through the action of cement, means for imparting to the overlaying means substantially at the end of its inward movement a movement in a different direction to increase its pressure on the upper, and means for pressing a portion 60 of the margin of the upper previously laid inwardly over the sole more firmly into adhering

relation to the sole while the upper is held under pressure by said overlaying means.

13. In a machine for shaping uppers over lasts, 5 overlaying means movable inwardly over the bottom of a last to lay the marginal portion of an upper over a sole on the last in position to adhere thereto through the action of cement, a tool for beating the upper, means for imparting to the overlaying means substantially at the end of its inward movement a movement in a different direction to increase its pressure on the upper, and means for actuating the beating tool while the upper is held under pressure by said overlaying means.

14. In a machine for shaping uppers over lasts, 10 a gripper for pulling an upper over a last and inwardly over a sole on the last, a member for laying the marginal portion of the tensioned upper over the sole, said member being so controlled as to move inwardly over the sole in a direction inclined toward its outer face to lay the upper over said face and also to move in another direction to press the upper more firmly against the sole, and a second member for beating the overlaid margin of the upper against the sole at one side 15 of the gripper.

15. In a machine for shaping uppers over lasts, 20 a gripper for pulling an upper over a last, an overlaying member for laying the margin of the tensioned upper over a sole on the last, a slide 25 movable in a direction inclined toward the outer face of the sole for imparting to said overlaying member its overlaying movement and for also moving the overlaying member toward the sole in a different direction to increase its pressure on 30 the upper, and a member arranged to act on the upper by impact at one side of the gripper to force the upper more firmly against the sole.

16. In a machine for shaping uppers over lasts, 35 a gripper for pulling an upper over a last, an overlaying member for laying the margin of the tensioned upper inwardly over a sole on the last, a slide 40 movable in a direction inclined toward the outer face of the sole for imparting to said overlaying member its inward movement, a member 45 for supporting the slide and for swinging it in a direction to increase the pressure of the overlaying member on the upper after the inward movement of the overlaying member has been substantially completed, a tool for beating the 50 upper at one side of the overlaying member, and means for operating the tool to beat the upper in time relation to the swinging movement of the slide.

17. In a machine for shaping uppers over lasts, 55 means for pulling an upper successively in different locations over a last having a sole thereon, means for laying the margin of the tensioned upper in each location inwardly over the sole, a member arranged to overlie the bottom of the 60 last for pressing upon the sole a portion of the margin of the upper laid inwardly over the sole in an earlier movement of the overlaying means, and means movable with said overlaying means for operating said pressing member. 65

18. In a machine for shaping uppers over lasts 70 means for pulling an upper successively in different locations over a last having a sole thereon, means for laying the margin of the tensioned upper in each location inwardly over the sole, automatic means for imparting to the overlaying means its inward movement and for also imparting to the overlaying means after said inward movement has been substantially completed a movement in a different direction to press the 75

upper more firmly against the sole, a tool arranged to extend inwardly over the bottom of the shoe for beating the overlaid margin of the upper against the shoe bottom, and means for actuating the beating tool to beat the upper in each cycle of the machine while the upper is held under pressure by said overlaying means.

5 19. In a machine for shaping uppers over lasts, means for pulling an upper successively in different locations over a last having a sole thereon, means for laying the margin of the tensioned upper in each location inwardly over the sole, automatic means for imparting to the overlaying means its inward movement and for also imparting to the overlaying means after said inward movement has been substantially completed a movement in a different direction to press the upper more firmly against the sole, a tool for beating the overlaid margin of the upper against the shoe bottom, and automatic means for actuating the beating tool before the upper is released by said overlaying means.

10 20. In a machine for lasting successively different portions of a shoe presented manually in different lasting positions, the combination with overlaying means movable inwardly over the bottom of a shoe in each lasting location to lay the marginal portion of the upper over the shoe bottom, of means for applying pressure to the overlaid margin of the upper comprising a member arranged to extend continuously over the shoe bottom, and means movable with said overlaying means for operating said member to press the upper.

15 21. In a machine for lasting successively different portions of a shoe presented manually in different lasting positions, the combination with a gripper for pulling an upper over a last in each lasting location, and overlaying means movable inwardly over the bottom of the last in a direction inclined toward its bottom face to lay the margin of the tensioned upper over a sole on the last, of a member for applying pressure to the overlaid margin of the upper, said member being arranged to extend continuously over the shoe bottom, and means for operating said member to press the upper in time relation to the inward movement of the overlaying means.

20 22. In a machine for lasting successively different portions of a shoe presented manually in different lasting positions, the combination with overlaying means movable in each lasting location inwardly over the bottom of the shoe in a direction inclined toward its bottom face to lay the marginal portion of the upper over a sole and to press it into position to adhere to the sole through the action of cement, of means automatically operative substantially at the end of each overlaying operation for forcing into firm and permanent adherence to the sole a portion of the upper previously laid over and pressed upon the sole in an earlier movement of said overlaying means.

25 23. In a lasting machine, the combination with means for pulling an upper successively in different locations over a last, fastening-inserting mechanism movable inwardly over the bottom of the last to lay the margin of each pulled over portion of the upper over a sole on the last and to fasten the upper to the sole by driven fastenings, and means for rendering the fastening-inserting mechanism ineffective to insert fastenings when lasting with cement instead of with driven fastenings, of means for applying pressure to a portion of the margin of the upper laid

inwardly over the sole in an earlier movement of the fastening-inserting mechanism to cause firm adhesion of the cemented engaging faces of the upper and the sole, said means comprising a member arranged to extend inwardly over the shoe bottom, and a second member connected to the fastening-inserting mechanism for delivering a hammer blow to the first-named member to force it against the upper.

30 24. In a lasting machine, the combination with means for shaping an upper over a last, fastening-inserting mechanism movable inwardly over the bottom of the last to lay the marginal portion of the upper over a sole on the last and to fasten the upper to the sole by driven fastenings, and means for rendering the fastening-inserting mechanism ineffective to insert fastenings when lasting the shoe without driven fastenings, of means arranged to be operated by said fastening-inserting mechanism when in position over the shoe bottom for pounding against the bottom of the shoe a portion of the margin of the upper previously laid inwardly over the sole by said fastening-inserting mechanism.

35 25. In a lasting machine, the combination with means for shaping an upper over a last, fastening-inserting mechanism movable inwardly over the bottom of a last to lay the marginal portion of the upper over a sole on the last and to fasten the upper to the sole by driven fastenings, and means for rendering the fastening-inserting mechanism ineffective to insert fastenings when lasting the shoe with cement instead of with driven fastenings, of a member for pounding against the shoe bottom a portion of the margin of the upper previously laid inwardly over the sole by said fastening-inserting mechanism, and means for operating said member to press the upper in time relation to the inward movement of the overlaying means.

40 26. In a lasting machine, the combination with means for shaping an upper over a last, fastening-inserting mechanism movable inwardly over the bottom of the last to lay the marginal portion of the upper over a sole on the last and to fasten the upper to the sole by driven fastenings, and means for rendering the fastening-inserting mechanism ineffective to insert fastenings when lasting the shoe with cement instead of with driven fastenings, of a presser arranged to overlie a portion of the upper previously laid inwardly over the sole by said fastening-inserting mechanism, and a member movable inwardly over the sole with said fastening-inserting mechanism for delivering to said presser a hammer blow to cause it to force the upper by impact against the sole.

45 27. In a lasting machine, the combination with means for shaping an upper over a last, means for fastening the upper to a sole on the last comprising a guide for fastenings movable inwardly over the bottom of the shoe to lay the marginal portion of the upper over the sole, a driver for driving fastenings, means for operating the driver, and means for rendering the driver in its driving movements ineffective to insert fastenings when lasting with cement instead of with driven fastenings, of a member for pressing against the shoe bottom a portion of the margin of the upper previously laid inwardly over the sole by said guide, and a second member movable with the driver for forcing said first-named member against the upper.

50 28. In a lasting machine, the combination with

means for shaping an upper over a last, means for fastening the upper to a sole on the last comprising a guide for fastenings movable inwardly over the bottom of the shoe to lay the 5 marginal portion of the upper over the sole, a driver for driving fastenings, means for operating the driver, and means for rendering the driver in its driving movements ineffective to insert fastenings when lasting with cement instead

of with driven fastenings, of a resilient member adapted to overlie the shoe bottom for pressing against the shoe bottom in a subsequent operation of the machine each overlaid marginal portion of the upper, and a member arranged to be operated by the driver-operating means for forcing said resilient member against the upper. 5

JOSEPH C. LISBON, SR.
